(57) **CLAIM**

(22) Filed: **Oct. 12, 2004**

The ornamental design for a nozzle holding portion of an adhesive dispenser, as shown and described.

(30) **Foreign Application Priority Data**

Apr. 14, 2004 (EP) 1658321U

DESCRIPTION

(51) **LOC (8) Cl.** **15-09**

FIG. 1 is a perspective view of the nozzle holding portion of an adhesive dispenser.

(52) **U.S. Cl.** **D15/144**

FIG. 2 is a rear perspective view thereof.

(58) **Field of Classification Search** D15/144-144.2;
239/1, 11, 71, 539, 536, 290, 423; 425/7,
425/208.2; 250/343, 339.12

FIG. 3 is a rear elevational view thereof.

See application file for complete search history.

FIG. 4 is a left side view thereof.

(56) **References Cited**

FIG. 5 is a front elevational view thereof.

U.S. PATENT DOCUMENTS

FIG. 6 is a right side view thereof.

5,148,982 A * 9/1992 Ekhoff 239/1

FIG. 7 is a top plan view thereof; and,

FIG. 8 is a bottom plan view thereof.

The broken line showing the nozzle is for illustrative purposes only and forms no part of the claimed design.
